UNITED STATES PATENT OFFICE.

FREDERICK JAMES THODY, OF GRAND FORKS, NORTH DAKOTA.

STOVEPIPE-DRUM.

1,032,964.

Specification of Letters Patent. Patented July 16, 1912.

Application filed October 19, 1911. Serial No. 655,538.

To all whom it may concern:

Be it known that I, FREDERICK JAMES THODY, citizen of the United States, residing at Grand Forks, in the county of Grand Forks and State of North Dakota, have invented new and useful Improvements in Stovepipe-Drums, of which the following is a specification.

My present invention pertains to heating drums of the stove-pipe type; and it consists in the peculiar and advantageous construction of drum hereinafter described and particularly defined in the claim appended.

In the drawing accompanying and forming part of this specification: Figure 1 is a vertical section illustrative of my novel construction of heating drum. Figs. 2 and 3 are horizontal sections taken in the planes indicated by the lines 2-2 and 3-3, respectively, of Fig. 1.

Similar letters of reference designate corresponding parts in all of the views of the drawings.

The drum A of my novel construction is formed of sheet-metal suitable to its purpose, is cylindrical in shape, and is provided with lower and upper openings a and b, surrounded by flanges c and d respectively; the lower flange c being designed to be fitted over the collar usually provided on top of a stove around the opening through which the products of combustion pass, and the flange d being designed for the connection of an ordinary smoke pipe or uptake. The stove and uptake or smoke-pipe mentioned form no part of my invention, and I have therefore deemed it unnecessary to illustrate the same.

In the drum A and at about its middle is fixed in suitable manner an apertured baffle plate or flame sheet B, which is of a size to occupy about one-half of the interior of the drum, as will be understood by reference to Figs. 1 and 2. Through the aperture e of the flame sheet or baffle plate B extends the air flue C of the device. The said air flue is of oblong form in cross-section, Fig. 2, and in the direction of its length it describes an obtuse angle; the apex of the angle being disposed in the aperture e of the plate or sheet B, and with its outer points adjacent the wall of the drum A. It will also be understood by reference to Fig. 1 that the flue C extends from the lower end to the upper end of the drum; also, that the lower end of the flue communicates with

a collar flange f on the lower end of the drum A, while the upper end of the flue communicates with a collar g on the upper end of the drum.

Connected through the medium of the collar f with the lower end of the flue C, is a tube D that extends to a point adjacent the floor h of an apartment, and is open at its lower end, while connected through the medium of the collar g with the upper end of the flue C is a tube E. This latter may open into the apartment in which the drum A is located, as illustrated, or if preferred said tube E may be carried up to a register in an apartment above the one in which is the drum A. This latter *per se* forms no part of my present invention, and I have therefore not regarded it as necessary to illustrate the same. I would further have it understood that when deemed desirable the drum A may be located in a room or apartment above that in which the stove or the like is located, in which event the smoke-pipe from the stove will be carried up through the floor of the upper apartment, and the drum A will be mounted on the pipe in said apartment. This latter arrangement *per se* is also not comprised in my present invention, and hence is not illustrated.

In the practical operation of my improvement the flames, smoke and other products of combustion from the stove enter the drum A through the opening a and in passing upward in the drum strike the lower half of the flue C at an angle and pass upward and around said portion of the flue, until said products bring up against the plate or sheet B. This latter is located above and in the same vertical plane as the opening a, and its office is to retard and change the course of the products of combustion so that after bringing up against the plate or sheet the products of combustion will be deflected to the opposite side of the drum, with reference to the plate or sheet, and passing the same will move upward against the upper half of the flue C and then after moving around the said upper half, pass through the upper opening b. Because of the peculiarly shaped and arranged air flue C, but little resistance is offered to the passage of the products of combustion through the drum A, and yet the said products are distributed throughout the interior of the drum and around the air flue C. From this it follows that a portion of the heat will be radiated

from the drum A and the remainder of the heat will raise the temperature of the flue C and the air circulating from and to the interior of the room through the said flue C. 5 It also follows that the plate or sheet B spreads the flames, and by so doing brings about the consumption of practically all the gas in the drum A, so that substantially all of the heat value in the products of combustion is utilized to heat the drum and the air flue.

It will be gathered from the foregoing that my improvement is simple and inexpensive in construction, and that the air flue 15 C lends increased stiffness and strength to the drum A, and at the same time serves in combination with the baffle plate or flame sheet B to assure thorough heating of the air from and to the interior of an apartment 20 through the drum A, and this without the air being contaminated by any of the products of combustion. This latter is due to the shape of the air flue C and its arrangement relative to the drum A and plate B 25 as specifically described.

Having described my invention, what I

claim and desire to secure by Letters-Patent, is:

The combination of an upright cylindrical drum having air and gas inlets at its lower end and air and gas outlets at its upper end and alined with the air and gas inlets respectively, an air flue that lengthwise describes an obtuse angle, fixed in the drum and extending between the air inlet and the air outlet, and a horizontal flame sheet fixed in the drum, adjacent the middle thereof, and occupying approximately one-half of the cross-section of the drum and having adjacent the drum wall an opening that receives the apex of the angle of the air flue; the said flame sheet being in alinement with the gas inlet and outlet so that the air flue crosses the path of the gases.

In testimony whereof I have hereunto set my hand in presence of two subscribing witnesses.

FREDERICK JAMES THODY.
